UNITED STATES PATENT OFFICE.

AGOSTINO SANTACROCE, OF ELYRIA, OHIO, ASSIGNOR OF THREE-TENTHS TO JOHN GRUMBOS AND THREE-TENTHS TO SPYRO SADARIS, BOTH OF ELYRIA, OHIO.

RUBBER HEEL.

1,313,118.

Specification of Letters Patent. Patented Aug. 12, 1919.

Application filed November 30, 1918. Serial No. 264,782.

To all whom it may concern:

Be it known that I, AGOSTINO SANTACROCE, a subject of the King of Italy, residing at Elyria, in the county of Lorain and 5 State of Ohio, have invented new and useful Improvements in Rubber Heels, of which the following is a specification.

This invention relates to rubber heels, and the principal object of the invention is to 10 form the heel with an inner part of greater resiliency than the rest of the heel, and the said part projecting below the tread surface of the heel, so that this part will remain in contact with the ground after the major 15 part of the tread has been lifted.

Another object of the invention is to provide this resilient part with a calk to prevent the heel from slipping.

Still another object of the invention is to 20 make the projecting portion which surrounds the calk of square formation for increasing the non-slipping action of the heel.

The invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a view of the tread face of the heel.

Fig. 2 is a section on line 2—2 of Fig. 1.
Fig. 3 is a top view.

In these views 1 indicates the body of the 40 heel, which has its top face of concave form and its tread face flat. The heel is provided with the usual nail-receiving holes 2 for securing the heel to the heel of the shoe. The center part of the heel is provided with a 45 tapered opening 3, and the top face of the heel is provided with a pair of annular-grooves 4 which are concentric with said opening. The inner groove is of greater depth than the outer groove and this inner 50 groove leaves an annular rim 5 around the larger end of the opening 3. The tread face of the heel is provided with a concentric groove 6, which is located between the upper grooves 4, as shown in Fig. 2. These grooves

make the center part of the heel of greater 55 resiliency than the rest of the heel so that the said center part with the opening therein will be pressed inwardly when the heel comes in contact with the ground and will spring outwardly again when the heel is 60 lifted. The tread part of this center part of the heel is provided with a square enlargement 7, which projects beyond the tread surface of the heel and this enlargement surrounds the small end of the opening. A rim 8 is formed on said enlargement around said opening and extends below the said enlargement. A calk 9 made of any suitable material is placed in the opening 3, and is prevented from passing entirely 70 through the said opening by means of the tapered formation of said opening and calk and also by the enlarged head 10 formed on said calk. As shown in Fig. 2, the head of the calk lies below the highest point of the 75 upper surface of the heel, so that the calk may be pressed upwardly when the heel is in place on the shoe.

It will thus be seen that when the heel is squarely in contact with the ground the center part of the heel will be pressed upwardly 80 until the tread surface of this part is in the same plane as the tread surface of the major part of the heel. As the foot is raised, the center part of the heel will spring back to 85 its normal position and thus remain in contact with the ground after the rear part of the heel has been raised off the ground. This will prevent the shoe from slipping on the sole and the front part of the heel. As 90 the center part springs back into normal position it will tend to dislodge dirt or snow from around the calk and from the groove 6. The square formation of the projection 7 will also act to prevent slipping of the 95 heel.

It is thought from the foregoing description that the advantages and novel features of my invention will be readily apparent.

I desire it to be understood that I may 100 make such changes in the construction and in the combination and arrangement of the several parts, provided that such changes fall within the scope of the appended claims.

What I claim is:—

1. A heel of the class described having a pair of concentric grooves in its upper face and a concentric groove in its lower face

forming a central resilient portion, the lower groove being located between the upper grooves.

2. A heel of the class described having a pair of concentric grooves in its upper face and a concentric groove in its lower face forming a central resilient portion, said

lower groove being located between the upper grooves, said resilient portion having a centrally located projection and an opening 10 and a calk seated in said opening.

In testimony whereof I affix my signature.

AGOSTINO SANTACROCE.
